UNITED STATES PATENT OFFICE

ALLEN C. PILCHER AND LAWRENCE C. PILCHER, OF LOUISVILLE, KENTUCKY, ASSIGNEES, BY DIRECT AND MESNE ASSIGNMENTS, TO THE RUSS MANUFACTURING COMPANY, OF CLEVELAND, OHIO, A CORPORATION OF OHIO

SIRUP PUMP

Application filed November 25, 1929. Serial No. 409,602.

Our said invention relates to dispensing pumps of the type used in soda fountains designed to deliver measured or predetermined quantities or sirup or the like.

5 The invention aims to provide an extremely simple and inexpensive form of pump which will be reliable in its action and extremely desirable in use.

The invention further aims to provide a device of this character which will be inoperative to deliver the sirup until the actuating handle has been actuated for a full stroke thereby preventing the delivery of less than the full amount.

15 The invention further aims to provide a construction in which the actuating member is normally operatively connected with the delivery member (pump piston) and will be automatically disconnected therefrom at the extremity of the inward movement of the actuating or handle member.

The invention also aims to provide simple economical means for preventing return of the actuating member prior to completion of 25 its full stroke which will be reliable in action.

The invention further aims to provide means for releasing the pump piston and also for controlling the return of the actuating member which will be of such a character as 30 not to require their being enclosed or encased to exclude contact of sirup in the tank.

The invention also aims to provide simple and efficient means by which the pump may be adjusted to deliver a greater or less amount 35 of sirup.

With these and other objects in view the invention includes the novel features of construction and arrangement and combination of parts hereinafter described, invention being 40 defined by the claims appended hereto.

What we at present regard as the preferred embodiment of the invention is illustrated in the accompanying drawings.

Figure 1 is a vertical section through our 45 improved pump with the sirup container indicated in dotted lines.

Figure 2 is a detail view partly in elevation and partly in section showing the actuating member and upper portion of the piston rod at the extremity of the inward stroke;

Figure 3 is a detail view in elevation of the piston rod locking and release means;

Figure 4 is a detail of the piston rod locking roller;

Figure 5 is a section on line 5—5 of Figure 1;

Figure 6 is a section on line 6—6 of Figure 1;

Figure 7 is a detail view of the outlet check valve;

Figure 8 is a section on line 8—8 of Figure 1;

Figure 9 is a vertical section (with parts broken away and the piston rod shown in elevation) of the adjustable pawl releasing sleeve and its support;

Figure 10 is a sectional detail of the sleeve 12; and

Figure 11 is an enlarged vertical section through the pump cylinder showing a modification of means for connecting the piston to its rod.

The pump is of the type which when in use, is inserted in a container holding the sirup or other liquid to be delivered, which container is indicated conventionally by the dotted lines 1. The pump comprises a cylinder 2 which is carried at the lower end of vertical columns 3 and 4, which are connected at their upper ends to a cover member 5 for the container, by which cover member the various parts of the delivery mechanism are carried.

The pump cylinder contains a piston 6 provided with posts 6^a controlled by an inwardly or upwardly opening check or flutter valve 6^b and is actuated by a piston rod 7 passing through an opening in the cylinder head 2^b, such cylinder head being preferably provided with an integral sleeve extension 2^b 80 to provide an elongated bearing for the piston rod. The column 4 is made hollow for delivery purposes and terminates at its upper end in a delivery spout 4^a while at its lower end where it joins the cylinder head it 85 is enlarged to form a valve chamber 4^c within which is located an upwardly opening check valve 8, cooperating with a valve seat formed at the upper end of the port 2^c in the cylinder head which places the valve 100

chamber in communication with the piston chamber or cylinder 2.

Normally the piston is held in elevated position as shown in Fig. 1 by a compression spring 9 surrounding the piston rod between the extension 2^b of the cylinder head and a collar 10 pinned or otherwise secured on the rod.

From the arrangement thus far described it will be obvious that when the piston is forced down against the pressure of the spring sirup will be drawn into the space within the cylinder above the piston. On the return stroke of the piston, under the action of the spring 9 the sirup is forced out of the cylinder into the delivery pipe.

For actuating the piston we provide the following mechanism:—

The upper portion of the piston rod is guided in a cross head 11 by means of a collar or sleeve 12, having a bore fitting the piston rod which is adjustably carried by the cross head, as by means of external screw threads engaging corresponding internal screw threads in a vertical passageway through the cross head and the upper end of the piston rod telescopically engages a lengthwise opening 13^a of an actuating member 13 mounted to have rectilinear reciprocating movement as hereinafter described and normally held elevated by spring 14. The rod 7 is provided adjacent its upper end with recesses in which are located dogs or pawls 7^a which are normally spring 35 pressed outwardly in position to engage the bottom face of the actuating member, so as to hold the parts in operative engagement and ensure that downward movement of the actuating member will impart corresponding movement to the piston rod. These pawls are spring pressed outwardly and have beveled outer faces whereby, when the piston rod is forced down until the pawls enter the sleeve or bushing 12 such beveled faces cause 40 them to be forced into the recesses until they are disengaged from the lower face of the actuating member whereupon the piston rod is immediately forced upward into the bore of the actuating member by the spring 9, 45 ejecting the sirup from the pump cylinder as hereinbefore described.

Preferably the bore of the actuating member is enlarged or flared outwardly above its lower end to relieve the frictional contact 50 of the pawls with the wall of the bore or recess.

By screwing the sleeve 12 up or down the point of disengagement of the piston rod and actuating member may be adjusted, and thus 55 the quantity of sirup delivered may be correspondingly regulated or varied.

Our preferred manner of constructing and mounting is to provide the cover member 5 with a tubular member or sleeve 15 having 60 an inturned annular flange 15^a at its lower

end for forming a guide for the lower part of the actuating member and also a seat for the lower end of the spring 14.

Said flange 15^a also cooperates with an annular shoulder or flange 13^b on the actuating member 13 to limit the upward movement thereof. Said actuating member has a reduced threaded extension 13^c at its upper end which engages a correspondingly threaded recess in a handle member 16 designed to receive the pressure of the hand of the operator, which member 16 has a depending sleeve or cylindrical skirt 16^a which telescopically fits the guide flange 15 and which also encloses the upper end of spring 14.

In order to compel the operator to push the piston rod sufficiently far to make a full stroke and insure the delivery at all times of the required or predetermined amount of sirup we provide means for automatically retaining the piston rod against return movement until the limit of its inward movement has been reached. This is preferably accomplished by providing the cross head with a roller carrying recess within which is located a roller 18, the wall of the recess adjacent the piston rod 7 having an opening through which a portion of the roller projects for contact with the piston rod, while the opposite or back wall of the recess is inclined as indicated at 17^a. The roller is normally forced upward by a spring 19 underlying the roller which tends to wedge the latter between the piston rod and said inclined wall.

A releasing pin 20 passes through a vertical opening in the cross head and has its lower end bearing against the roller and its upper end or head in the path of movement of the lower face of the actuating member so that when the latter has been pushed down far enough to cause a full stroke of the piston the releasing pin is depressed which pushes the roller down and out of its wedging position and allows the piston rod to be freely returned to initial position under the action of 100 spring 9.

It will be understood that the parts are so arranged that the pawls or dogs 7^a are forced inward into disengaging position just after the actuation of the releasing pin 20.

We find it desirable to provide means for rotating the piston rod during its rectilinear movements and thereby distribute the wear due to the action of the pawls on the upper end of the sleeve. A simple manner of effecting this is to provide the sleeve 12 with a helical internal groove 12^a which has a tendency to effect such rotation.

With a roller check means such as disclosed a slight upward movement of the piston rod will take place before the roller actually grabs or binds the rod, and this movement would cause the delivery of a small amount of sirup in the absence of some preventative therefor. To avoid this we provide the 125

piston rod with a piston having a compensating movement on the rod as shown in Fig. 11. To this end the rod is provided with a reduced portion 7^b on its lower end which slidably engages a central opening in the piston 6. The lower end of the rod has a threaded recess which is engaged by a screw 7^c, the head of which has an annular groove *c* which forms a seat for the lower end of a compression spring 21 which normally holds the piston pressed up against the annular shoulder formed by the reduced portion of the rod. The spring however, exerts such light pressure, that if the rod is allowed by the operator to move up before a full stroke is made, the piston will move downward on the rod by an amount equal to the upward movement of the rod before the locking roller acts and thus delivery of syrup by such partial stroke will be prevented.

While we have described and illustrated with particularity what we consider as the preferred embodiment of our invention it will be obvious that various changes and modifications could be made without departing from the spirit of our invention.

Having thus described our invention what we claim is:

1. In a liquid dispensing pump, a piston, an endwise movable piston rod in permanent operative connection with the piston, an endwise movable piston rod actuating member having fixed hand control means, said piston rod and hand operated actuating member being normally operatively connected together for unitary movement, and means rendered operative during such unitary movement for disconnecting said elements for relative endwise movement.

2. In a liquid dispensing pump, a piston, an endwise movable piston rod in permanent operative connection with the piston, an endwise movable actuating rod having fixed hand control means, said actuating rod normally having actuating engagement with said piston rod, for unitary movement, and adjustable means for effecting disengagement of said rods at predetermined places in the unitary endwise movement thereof.

3. A liquid dispensing pump having a piston and piston rod permanently and operatively connected together, spring means tending normally to hold said rod elevated, an actuating rod, spring means for holding said actuating rod elevated, said rods being arranged to have unitary and also relative endwise movement, a dog normally connecting said rods for unitary movement, and means rendered operative by the unitary endwise movement for operating said dog to disengage said rods for relative endwise movement.

4. A liquid dispensing pump having a piston and piston rod permanently and operatively connected together, spring means

tending normally to hold said rod elevated, an actuating rod, spring means for holding said actuating rod elevated, said rods being arranged to have unitary and also relative endwise movement, a dog normally connecting said rods for unitary movement, and adjustable means rendered operative by the unitary endwise movement for operating said dog to disengage said rods for relative endwise movement.

5. In a liquid dispensing pump, an endwise movable piston rod, an endwise movable actuating rod, means normally connecting said rods for unitary movement, means rendered operative by such unitary movement for disconnecting said rods, and means external to the piston rod for positively locking the piston rod against return movement until it has moved to the limit of its stroke.

6. In a liquid dispensing pump, a piston, a piston rod in permanent operative connection with the piston, an aligned actuating rod having fixed hand control means, one of said rods having an abutment and the other dog means normally engaging said abutment to operatively connect said rods for unitary movement, and means rendered operative by such unitary movement for operating said dog means to permit relative movement of said rods.

7. In a liquid dispensing pump, a piston, a piston rod in permanent operative connection with the piston, spring means normally elevating said rod, an actuating rod having a tubular bore to telescopically receive said rod, spring means tending normally to elevate said actuating rod, a yieldable dog carried by said piston rod normally engaging a part on said actuating rod to connect the rods for unitary movement, and means rendered operative by such unitary movement for moving said dog to release position.

8. In a liquid dispensing pump, a piston, a piston rod in permanent operative connection with the piston, a spring normally holding said rod elevated, an actuating rod having telescopic relation to said piston rod, means tending normally to hold said actuating rod elevated, means normally connecting said rods for unitary movement, means rendered operative at the extremity of such unitary movement for disconnecting said rods for telescopic movement, means for positively locking the piston rod against retrograde movement during such unitary movement, and means rendered operative by the completion of movement of the actuating rod for operating said locking means to permit retrograde movement of the piston rod.

9. In a liquid dispensing pump, a piston rod, spring means normally elevating said rod, an actuating member having a tubular bore to telescopically receive said rod, spring means tending normally to elevate said actuating member, a yieldable dog carried by

the piston rod and normally engaging a part on the actuating member to connect said elements for unitary movement, means rendered operative at the extremity of the unitary movement for moving said dog to release position, detent means normally engaging said piston rod to prevent retrograde movement thereof during such unitary movement and means operated by the actuating member for moving said detent means to release position substantially at the extremity of said unitary movement.

10. In a liquid dispensing pump a piston rod, an actuating rod having a tubular bore 15 to telescopically engage said rod, spring means for holding both said rods normally elevated, a yieldable dog carried by the upper end of the piston rod and normally engaging a part on the actuating rod, a stationary 20 sleeve through which the upper end of the piston rod passes, said yieldable dog having an inclined face to coact with the sleeve to move the dog to release position.

11. In a liquid dispensing pump, a piston 25 rod, an actuating rod having a tubular bore to receive the upper end of said rod, said piston rod having a recess adjacent its upper end, a yieldable dog located in said recess and normally projecting therefrom to abut 30 a part on the actuating rod, the projecting part of said dog having an inclined face, and an adjustable member arranged in the path of said inclined face for moving the dog inward into the recess.

35 12. In a liquid dispensing pump, a piston rod, an actuating rod having a tubular bore to telescopically receive said rod, spring means tending to elevate said rods, said piston rod having a recess, a yieldable dog located in 40 said recess and normally projected therefrom to engage a part on the actuating rod, said dog having an incline on its projecting face, a fixed part encircling said rod, an adjustable sleeve carried by said fixed part through 45 which said piston rod passes, said adjustable sleeve cooperating with said inclined face of the dog.

13. In a liquid dispensing pump, a piston rod, an actuating rod having a tubular bore 50 to telescopically receive said rod, spring means tending to elevate said rods, said piston rod having a recess, a yieldable dog located in said recess and normally projected therefrom to engage a part on the actuating rod, said dog having an incline on its projecting face, a fixed part encircling said rod, an adjustable sleeve carried by said fixed part through which said piston rod passes, said adjustable sleeve cooperating with said inclined face of the dog, and means for effecting rotation of the piston rod during its end- 60 wise movements.

14. In a liquid dispensing pump a piston rod, a spring tending normally to elevate 65 said rod, an actuating rod, a spring tending

normally to elevate the same, said actuating rod having a bore to telescopically receive said piston rod and a downwardly facing abutment face, said piston rod having recesses adjacent its upper end, yieldable dogs located in said recess and having parts normally projecting therefrom to engage said abutment face and having inclined side faces, a fixed part, a sleeve carried by said fixed part to cooperate with the inclined faces of the dogs, a roller detent carried by said fixed part positioned to normally engage said piston rod, and a push pin slidably carried by said fixed part and arranged to be operated by said downwardly facing abutment of the actuating rod for moving said roller detent to release position.

15. In a liquid dispensing pump, a pump cylinder, a piston, a piston rod, spring means tending normally to hold said rod elevated, an actuating rod, spring means tending to hold the same elevated, said rods being arranged to have unitary and also relative endwise movement, a dog normally operatively connecting said rods for unitary movement, friction detent means normally engaging said piston rod to prevent retrograde movement during such unitary movement, means rendered operative at the extremity of the unitary endwise movement for releasing said friction detent and dog.

16. In a liquid dispensing pump, a pump cylinder having a closed upper end provided with a liquid discharge outlet, a check valve in said outlet, a piston rod passing through said end, a valved piston mounted on said rod to have limited movement lengthwise thereof, a spring tending to move said piston to the limit of its upward movement, spring means tending to elevate said piston rod, an actuating rod capable of telescopic movement relative to said piston rod, means normally connecting said rods for unitary movement, means rendered operative at the extremity of such movement for disconnecting said rods, detent means for preventing premature retrograde movement of the piston rod, and means rendered operative at the extremity of the unitary movement for releasing said detent means.

17. In a liquid dispensing pump according to claim 14, a piston connected to said piston rod to have limited movement lengthwise thereof.

In testimony whereof we affix our signatures.

ALLEN C. PILCHER.
LAWRENCE C. PILCHER.
